UNITED STATES PATENT OFFICE.

CARL G. THOMPSON, OF ST. LOUIS, MISSOURI.

BOW GUN.

Application filed February 8, 1926. Serial No. 86,727.

My invention relates to bow-guns, and, it is a distinct and practical improvement to overcome certain practical objections to, and defects in, the present types of bow-guns.

5 The object of my present invention is to provide a bow-gun of high efficiency, power and general utility for which such a device can be used, as for instance by police departments to shoot tear, or gas bombs to disperse a mob, by fire departments in shooting a prepared ball of twine to provide connecting means of rescue to occupants of high buildings out of reach of ladders, or shut off from fire escapes and by individuals interested in archery as a popular outdoor or indoor sport, amusement and exercise.

20 A further object of the invention is to provide a bow-gun which possesses advantages in points of simplicity and efficiency, and, at the same time proves itself comparatively inexpensive in manufacture.

25 With the above and other objects in view, the invention consists in the novel features of construction, arrangement and combination of parts hereinafter more fully described and finally pointed out in the claims hereto appended.

30 Referring to the accompanying drawings forming a part of this specification, wherein like characters of reference denote similar parts throughout the several views:

Fig. 1 is a side elevation of the wooden bow member.

35 Fig. 2 is a plan view of the ribbed metallic reinforcing strip which is applied to the wooden bow member.

Fig. 3 is a side elevation of a bow-gun embodying the features of my invention.

40 Fig. 4 is a sectional view taken on line 4-4 of Fig. 3.

Fig. 5 is a detail of the rear end of the guide member.

45 Fig. 6 is a front elevation of the slidable cross head mounted upon the aforesaid guide member.

Fig. 7 is an end elevation of the bow gun.

Fig. 8 is a front elevation of the arrow rest and guide plate as attached to the bow.

50 Fig. 9 is a modified form of bow gun.

In carrying out the aim of my present invention, I employ a suitable resilient wooden bow member 1 of any desired shape and size, preferably tapering towards its ends and having its ends suitably and permanently bent or curved forwardly, as at 2, as shown in Fig. 1.

A suitable resilient metallic facing strip 3 is suitably fixed to the forward face of the wooden bow member 1. This strip is provided with a pair of opposed and aligned longitudinally directed ribs 4 which are pressed outwardly in the strip and gradually tapered to a point at their outer ends, as clearly shown in Fig. 2. The extremities of the resilient facing strip 3 are bifurcated to provide the end loops 5 to pivotally receive the arms 6 of the wire loop connections 7.

A second resilient facing strip 8 may, or may not be used as desired, and when used, it is suitably fixed to the rear face of the wooden bow member 1. This strip 8 is also provided with a pair of spaced and aligned longitudinally directed ribs 9 which are pressed outwardly in the strips and gradually tapered to a point at their outer ends. A very powerful bow-gun of predetermined strength preferably employs both facing strips 3 and 8 wherein a lighter, cheaper and weaker bow-gun will employ but one of the facing strips, as is manifest.

A suitable thumb guard member 10 provided with the loops 11 is suitably fixed to the rear face of the bow-gun member 1 midway the ends thereof, as shown in Fig. 3. The thumb guard member 10 is provided with an opening 12 which registers with an opening 13 in the wooden bow member 1 and receivable in these openings is a tubular guide rod 14 which is removably fixed to the bow member 1 by means of a screw threaded fastening device 15 which passes through the facing strip 3 and a nut 16 embedded in the front face of the wooden bow-member 1, as clearly shown in detail in Fig. 4. The guide rod 14 is provided at its rear end with a suitably fixed head 17 to limit the arching movement of the bow-gun member 1, and its facing strips, thereby preventing any undue bending of the bow members when arching the same.

A suitable cross-head 18 having the finger recesses 19 is slidably mounted upon the guide rod 14 and is provided with ears 20 to which the inner ends of a pair of endless bow cords 21 are suitably connected, the opposite or outer ends of the cords being suitably connected with the wire loop connections 7 which when at their normal inactive position are in contact with the rear face of the curved ends of the bow members, as shown in Fig. 3, and with the

sliding cross head 18 in contact with a suitable buffer member 22 carried by the outer face of the thumb guard member 10.

The sliding cross head member 18 is provided with a laterally directed socket member 23 adapted to receive the rear end of a suitable arrow 24 and the bow-member 1 is provided with a suitable laterally directed rest and guide plate 25 provided with a 10 suitable notch, or recess 26 for the arrow to rest upon, as clearly shown in Figs. 4, 6, 7 and 8 to afford a means for perfect alignment of the arrow.

The wooden bow member 1 is provided 15 with a suitable front sight member 27 to the rear of the arrow rest and guide plate 25 and the slidably mounted cross head 18 is provided upon the socket member 23 with a suitably notched rear sight member 28, as 20 clearly shown in Fig. 7, thereby affording a means of acquiring efficiency in marksmanship equal to the same as provided in modern rifles.

In the modification shown in Fig. 9, I 25 have eliminated the wooden bow member 1 and attached the two metallic bow member facing strips 3 and 8 together in any suitable manner, otherwise the construction is the same throughout, as will be apparent 30 from the drawing.

From the foregoing description, it is evident that I provide a bow-gun having predetermined and uniform strength, that the bending or arching of the bow is limited 35 and that I provide a device which permits the operator to accurately aim at objects at which he is shooting. It will also be observed that I provide a bow-gun which is substantially straight in its normal position 40 and is only curved or arched when an arrow is to be projected thereby.

The many advantages of the herein described invention will readily suggest themselves to those skilled in the art to which it 45 appertains.

I do not desire to be understood as limiting myself to the exact details of construction and arrangement of parts as herein described and illustrated, as it is manifest 50 that variations and modifications may be made without departing from the spirit and scope of my invention and the terms of the following claims, hence I wish it to be understood that I reserve the right to make 55 any such changes, or modifications as may fairly fall within the scope of the appended claims when fairly construed.

What I claim is:

1. In a bow-gun structure, a resilient 60 wooden bow member, a resilient metallic facing strip fixed to said wooden bow member, a guide rod fixed to and directed rearwardly from the center of said wooden bow member, a cross-head slidably mounted on 65 said guide rod and bow cords connecting

the slidably mounted cross-head with the ends of the bow member.

2. In a bow-gun structure, a resilient wooden bow member, a resilient metallic facing strip fixed to said wooden bow member, 70 a guide rod fixed to and directed rearwardly from the center of said wooden bow member, a cross-head slidably mounted on said guide rod, a thumb guard fixed to the bow member and disposed between the bow 75 member and the slidably mounted cross-head and bow cords connecting the slidably mounted cross head with the ends of the bow member.

3. In a bow-gun structure, a resilient 80 wooden bow member, a resilient metallic facing strip fixed to said wooden bow member, a guide rod fixed to and directed rearwardly from the center of said wooden bow member, a cross head slidably mounted on 85 said guide rod, a thumb guard fixed to the bow member and disposed between the bow member and the slidably mounted cross-head, bow cords connecting the slidably mounted cross head with the ends of the 90 bow member and a buffer fixed to the outer face of the thumb guard against which the slidably cross-head may strike when released from its outer position upon the guide rod 95 for projecting an arrow.

4. In a bow-gun structure, a resilient bow member, a guide rod fixed to and directed rearwardly from said bow member, a cross head having an arrow receiving socket 100 slidably mounted upon said guide rod, a front sight member fixed to said bow member and a rear sight member fixed to said 105 slidably mounted cross head.

5. In a bow-gun structure, a resilient bow member, a thumb guard fixed to said bow 110 member, a buffer carried by said thumb guard, a guide rod fixed to and directed rearwardly from said bow member, a cross head having an arrow receiving socket 115 slidably mounted upon said guide rod, a front sight member fixed to said bow member and a rear sight member fixed to said 120 slidably mounted cross head.

6. In a bow-gun structure, a resilient bow member, a thumb guard fixed to said bow 125 member, a buffer carried by said thumb guard, a guide rod fixed to and directed rearwardly from said bow member, a cross head having an arrow receiving socket slidably mounted upon said guide rod, arrow supporting means fixed to said bow member, a front sight member fixed to said bow member and a rear sight member fixed to said 130 slidably mounted cross head.

7. In a bow-gun structure, a resilient wooden bow member, a resilient metallic facing strip fixed to the front face of said bow member, loops formed at opposite ends of said facing strip, links pivotally connect- 135

- rear face of said bow member, a guide rod fixed to and directed rearwardly from said bow member, a cross head slidably mounted upon said guide rod, bow-cords connecting the cross head with the aforesaid links, arrow supporting means fixed to said bow member, a socket member fixed to said cross head for receiving the rear end of an arrow, a front sight member fixed to the bow member to
10. the rear of and above said arrow supporting member, a rear sight member fixed to the socket member of the cross head and means for limiting the rearward movement of the cross head upon said guide rod.
15. 8. In a bow-gun structure, a substantially straight resilient wooden bow member having its ends permanently curved forwardly, a ribbed resilient metallic facing strip fixed to the front face of said bow member, loops formed at opposite ends of said facing strip, links pivotally connected to said loops, a thumb guard fixed to the rear face of said bow member, a guide rod fixed to and directed rearwardly from said bow member, a cross head slidably mounted upon said guide rod, bow cords connecting both ends of the bow member with said cross head, an arrow rest plate fixed to the bow member, a socket member carried by the cross head for receiving the rear end of an arrow, a front sight member fixed to the bow member and a rear sight member fixed to said cross head.
20. 9. In a bow-gun structure, a bow member consisting of a pair of substantially straight united metallic strips having longitudinally directed ribs formed therein and tapering toward their outer ends, a thumb guard fixed to said bow member, a guide rod fixed to said bow member and directed rearwardly therefrom, a cross head slidably mounted upon said guide rod, bow cords connecting both ends of the bow member with said cross head, an arrow rest plate fixed to the bow member, a socket member carried by the cross head for receiving the rear end of an arrow; a front sight member fixed to the bow member and a rear sight member fixed to said cross head.
25. 10. In a bow-gun structure, a substantially straight resilient wooden bow member having its ends permanently curved forwardly, a ribbed resilient metallic facing strip fixed to the front face of said bow member, loops formed at opposite ends of said facing strip, links pivotally connected to said loops, a ribbed resilient metallic fac-
30. ing strip fixed to the rear face of the bow member, a thumb guard fixed to the rear face of said bow member, a guide rod fixed to and directed rearwardly from said bow member, a cross head slidably mounted upon
35. 11. In a bow-gun structure, a bow member consisting of a pair of substantially straight united metallic strips having longitudinally directed ribs formed therein and tapering toward their outer ends, a thumb guard fixed to said bow member, a guide rod fixed to said bow member and directed rearwardly therefrom, a cross head slidably mounted upon said guide rod, bow cords connecting both ends of the bow member with said cross head, an arrow rest plate fixed to the bow member, a socket member carried by the cross head for receiving the rear end of an arrow; a front sight member fixed to the bow member and a rear sight member fixed to said cross head.
40. 12. In a bow-gun structure, a bow member consisting of a pair of substantially straight united metallic strips having longitudinally directed ribs formed therein and tapering toward their outer ends, a thumb guard fixed to said bow member, a guide rod fixed to said bow member and directed rearwardly therefrom, a cross head slidably mounted upon said guide rod, bow cords connecting both ends of the bow member with said cross head, an arrow rest plate fixed to the bow member, a socket member carried by the cross head for receiving the rear end of an arrow; a front sight member fixed to the bow member and a rear sight member fixed to said cross head.
45. 13. In a bow-gun structure, a bow member consisting of a pair of substantially straight united metallic strips having longitudinally directed ribs formed therein and tapering toward their outer ends, a thumb guard fixed to said bow member, a guide rod fixed to said bow member and directed rearwardly therefrom, a cross head slidably mounted upon said guide rod, bow cords connecting both ends of the bow member with said cross head, an arrow rest plate fixed to the bow member, a socket member carried by the cross head for receiving the rear end of an arrow; a front sight member fixed to the bow member and a rear sight member fixed to said cross head.

In testimony whereof, I have hereunto affixed my signature.

CARL G. THOMPSON.
